(57) **CLAIM**

The ornamental design for a display fixture, as shown and
described.

DESCRIPTION

FIG. 1 is a top and front perspective view of a display
fixture, showing an embodiment of our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines depict unclaimed subject
matter only and form no part of the claimed design. As a
clarification due to the small size of some of the features
depicted in broken lines, the small coupling members along
the top of the fixture and the small bolts, nuts, and holes on
the supporting legs are unclaimed in both illustrated embodiments.
